REVERSIBLE PROPELLER

Alastair Peter Hunter, Orillia, Ontario, and August Eric Pearson, Toronto, Ontario, Canada

Application November 3, 1936, Serial No. 108,984

1 Claim. (Cl. 115—34)

Our invention relates to improvements in reversible propellers, and the object of the invention is to devise a propeller of this type in which the propeller shaft is divided into two members and is actuated by the longitudinal movement of either member in relation to the other to give the blades the required set, and in which the blades, when set, are more rigidly held in their set position, and it consists essentially of the arrangement and construction of parts as hereinafter more particularly explained.

Fig. 1 is a longitudinal section through our device.

Fig. 2 is a plan view of our device.

15 Fig. 3 is a sectional detail on line 3—3 Fig. 1.

Fig. 4 is a sectional detail on line 4—4 Fig. 1.

Fig. 5 is a sectional detail on line 5—5 Fig. 1.

Fig. 6 is a sectional view of a modified construction.

20 Fig. 7 is a sectional plan view of the construction illustrated in Fig. 6.

Fig. 8 is a sectional detail on line 8—8 Figs. 6 and 7.

Fig. 9 is a view partially in elevation and partially in section of a further modification.

25 Fig. 10 is an enlarged transverse sectional view on line 10—10 Fig. 9.

Fig. 11 is a similar view to Fig. 10 on line 11—11

Fig. 9.

30 Fig. 12 is a sectional detail on line 12—12 Fig. 3.

In the drawing like characters of reference indicate corresponding parts in each figure.

1 indicates the engine shaft on which the propeller body 2 forming a gear housing is mounted

35 at one end. The body 2 is divided centrally, the divided parts being secured together by bolts 21.

In order to connect the engine shaft 1 to the body 2, one body portion is provided with a sleeve portion 2^x having an inwardly tapered orifice 2⁰ into

40 which the tapered end 1⁰ of the engine shaft 1 is driven. The inner end of the portion 2^x is provided with a reduced threaded stem 1¹ on which

45 a nut 3 is screwed to bear against the inner end of the sleeve portion 2^x.

45 4 is a sleeve portion extending from the other body portion diametrically opposite and in axial alignment with the sleeve portion 2^x.

Internally the sleeve portion 4 is provided with a cylindrical enlargement 5 forming end shoulders 5^x and 5⁰,

50 an intermediate cylindrical portion 6 and a squared portion 7. 8 and 9 are diametric orifices centered on the dividing line between the members of the body 2 and provided at their outer ends with annular concentric recesses 8^x and 9^x.

55 10 and 11 are the propeller blades provided with

circular inner ends 10^x and 11^x turnably fitting the recesses 8^x and 9^x from which extend studs 10⁰ and 11⁰ turnably fitting the orifices 8 and 9. The opposing ends of the studs 10⁰ and 11⁰ carry bevel gears 12 and 13 which are held in axial alignment by a pin 14 fitting in axially aligned orifices 10¹ and 11¹ (see Fig. 5).

15 15 is a supporting strut which depends in the usual manner at the stern of the boat and is provided at its lower end with a bearing sleeve 10⁵ 15^x in which the sleeve portion 4 of the propeller body turnably fits.

16 16 is a control shaft divided into two portions one of which is journalled in the sleeve 4 and provided with an internally threaded sleeve enlargement 16^x. The other portion of the control shaft forms a thrust member and comprises a squared portion 17 slidably fitting the squared portion 7 of the sleeve 4 from one end of which extends a worm 17^x engaging the internal thread of the 20 sleeve 16^x and from the other end of which extends a reduced portion 17⁰ mounted at its opposite end in a bearing orifice 15⁰. 18 is a block carried on the reduced portion 17⁰ between two collars 19 and 19^x and provided with a transverse groove 18^x. 20 is a control spindle, to the lower end of which is secured a disc 21 having a projection 21^x extending into the groove 18^x.

25 By turning the spindle 20 the projection 21^x engages the groove 18^x exerting through the 30 block 18 a longitudinal thrust on the portions 17⁰, 18 and 17^x forcing the worm 17^x longitudinally of the sleeve 16^x rotating the same by its engaged thread together with the gear 22. The gear 22 meshing with gears 12 and 13 rotates them in 35 opposite directions together with the blades 10 and 11 to set them either for forward or rearward direction drive as required.

If it is desired to operate the reversing mechanism from a position forward, we divide the engine shaft and provide a slidable connection between the divided parts as indicated at 1^x. 23

40 and 24 are thrust bearings. 25 is a sleeve mounted on the engine shaft between the thrust bearings 23 and 24. 26 and 27 are bearings lo-

45 cated at each side of the sleeve in which are mounted shafts 28 to each of which is secured a crank 29 connected by links 30 to a suitable operating lever not shown. The opposite sides

50 of the sleeve are recessed as indicated at 31 in 50 which recesses fit discs 32 eccentrically mounted on the shafts 28 to engage the opposite ends of the recesses 31. By swinging the cranks 29 forward or back the eccentrics engage the ends of the recesses to force the sleeve 25 in a correspond-

ing direction against the thrust bearings carrying the movable portion of the engine shaft longitudinally together with the propeller body carried thereby and forcing the cylinder 16 longitudinally of the worm 17^x to rotate the gear 22 and thereby adjust the blades 10 and 11 to the forward and reverse positions.

In Figures 6, 7 and 8 we have shown a modified structure in which the gears 12 and 13 of Figures 1-5 are replaced by crank arms 33 and 34 provided with crank pins 35 and 36. Links 37 and 38 are mounted at one end on the crank pins 35 and 36 and pivoted at the opposite end to a head 39 formed integral with the control shaft 40 which is operated in a similar manner to that above described in connection with Figures 1 to 5.

In Figures 9 to 11 we show a triple bladed propeller to which the construction of Figures 6 to 8 is applied. In Figures 9 to 11, 41 is the engine shaft and 42 the control shaft journaled in the propeller body 43. 44, 45 and 46 are the stub ends of the propeller blades journaled in the body 43 in a manner similar to that previously described with the exception that instead of

the pin 14 we employ a spider 47 having pin projections 48 extending into orifices 49 formed axially in the stub ends and the head 50 corresponding to the head 39 of Figs. 6 and 7 is provided with three jaws 51 instead of two connected by links 52 to the cranks 53 of the propeller blades 44, 45 and 46.

What we claim as our invention is:—

The combination with the depending stern strut of a boat and the rotatable propeller, the blades of which are adjustable around their axis, of a longitudinally movable member, means operated thereby for imparting the required set to the propeller blades, a vertical control spindle mounted in the strut, a disc secured to the lower end of the strut, a projection extending from the lower face of the disc, a block mounted freely on the longitudinally movable member, a collar secured to such member at each side of the block, and a groove formed in the upper face of the block into which the disc projection slidably fits.

ALASTAIR PETER HUNTER.
AUGUST ERIC PEARSON.
